(57) **CLAIM**

The ornamental design for men's boxer briefs, as shown and described.

DESCRIPTION

FIG. 1 is a front elevation view of the men's boxer briefs of the present design, shown in a state whereby the fastener strips are engaged;

FIG. 2 is an interior plan view of the men's boxer briefs of FIG. 1 laid flat;

FIG. 3 is an exterior plan view of the men's boxer briefs of FIG. 1 laid flat;

FIG. 4 is a side elevation view of the men's boxer briefs of FIG. 1;

FIG. 5 is a side elevation view of the hook and loops fasteners of the men's boxer briefs of FIGS. 1-4; and,

FIG. 6 is an enlarged detail view of the tab section located on the men's boxer briefs of FIGS. 1-5. The broken lines are boundaries of the detail and form no part of the claimed design.
